PAGE 2

Figure 1 is a perspective view of an electromagnetic relay with cover, showing my new design;

Figure 2 is a top plan view;

Figure 3 is a side elevational view; the opposite side being substantially a mirror image thereof;

Figure 4 is a bottom plan view;

Figure 5 is a front elevational view; and

Figure 6 is a rear elevational view thereof.

The dominant features of my new design are shown in solid lines in the drawing.

I claim:

The ornamental design for an electromagnetic relay with cover, as shown and described.
